UNITED STATES PATENT OFFICE.

PETER F. VAN HALDER, OF SHARON, PENNSYLVANIA.

ADVERTISING DEVICE.

No. 872,700.

Specification of Letters Patent.

Patented Dec. 3, 1907.

Application filed February 13, 1907. Serial No. 357,145.

To all whom it may concern:

Be it known that I, PETER F. VAN HALDER, citizen of the United States, residing at Sharon, in the county of Mercer and State of Pennsylvania, have invented certain new and useful Improvements in Advertising Devices, of which the following is a specification.

This invention has for its object a simple and unique advertising device which consists of disks centrally pivoted together and adapted to contain advertisements, photographs, or the like, as well as days and weeks of the months of the year, so that the device may be used as a pocket or other calendar, and at the same time so arranged and constructed as to display the advertisement, photograph, or other display matter, whenever in use.

With this and other objects in view as will more fully appear as the description proceeds, the invention consists in certain constructions and arrangements of the parts which I shall now specifically describe and claim.

For a full understanding of the invention, reference is to be had to the following description and accompanying drawings, in which:

Figure 1 is a front face view of my improved advertising device; Fig. 2 is a rear view thereof; Fig. 3 is an edge view.

Corresponding and like parts are referred to in the following description and indicated in all the views of the drawings by the same reference characters.

My improved advertising or display device comprises an intermediate disk 1, a front disk 2, and a back disk 3, all of which are centrally pivoted together by means of a pivot stud 4. It is to be particularly noted that while all the disks are concentric, the middle or intermediate disk 1 is of smaller diameter than the outside disks 2 and 3, and that it is provided at one point with an integral extension 5 which serves as a handle and is preferably provided with an aperture 6 by which the entire device may be hung upon a nail or the like. By forming the middle disk 1 of slightly smaller diameter than the outside disks, it is evident that the said middle disk may be readily turned with respect to the other two disks by grasping the margins of the two outer disks between one's finger

and thumb of one hand and turning the middle disk by means of the handle extension 5, with the other hand, the pressure on the edges of the outer disks tending to bow them over slightly and spread them apart so as to permit the middle disk to have free rotation without undue frictional engagement with the opposite walls of the outer disks 2 and 3, it being of course understood, as shown in the drawings, that the two outer disks are free from connection at the edges.

The middle disk 1 is designed to contain or display upon one face, the calendar months of the year arranged in circular series as indicated at 7 and said disk may display on its other face a series of advertisements, or have a series of spaces for photographs or the like, blocked out and corresponding to the various months of the year shown on the opposite face. To display this advertising matter or photographs, as well as the different months, the outside disks 2 and 3 are respectively provided with coinciding openings 9 and 10, such openings being preferably of the same shape as the spaces or blocks of display matter on the opposite faces of the middle disk 1. The front disk 2 may display an advertising matter on its outer face below its opening 9 and similarly the back disk 3 may also contain an advertisement.

From the foregoing description in connection with the accompanying drawing, it will be seen that I have provided a very cheap and simple advertising or display device which may be made of any material of different sizes, so as to constitute a pocket calendar and advertising medium, or the like combined, or a wall device, in which latter event the handle extension or lug 5 is provided with an aperture 6, as above noted.

Having thus described the invention, what is claimed as new is:

As an improved article of manufacture, the herein described display device consisting of three disks face to face and pivotally connected together at the center, the intermediate disk being provided with an integral handle extension and containing display matter, and the two outer disks being of greater diameter than the intermediate disk and free from connection with each other and the intermediate disk, except with the pivot, one of said outer disks being formed with a side opening extending there-

through in registry with the display matter of the intermediate disk, the said outer disks being susceptible to bowing by pressure exerted on them from their margins inwardly, 5 whereby pressure applied inwardly at diametrically opposite points of the device will result in spreading apart the outer disks so as to permit the intermediate disk to have

free rotation without undue frictional engagement with the opposite walls of the outer disks. 10

In testimony whereof I affix my signature in presence of two witnesses.

PETER F. VAN HALDER. [L. S.]
